SHOE BUCKLE

Larry Albiniano, Providence, R.I., assignor to F. Ronci Co., Inc., Centerdale, R.I., a corporation of Rhode Island

Filed May 16, 1963, Ser. No. 280,840
2 Claims. (Cl. 24—191)

My present invention relates to the buckle art and more particularly to a novel construction of a shoe buckle.

The principal object of the present invention is to provide a novel grip type buckle construction which locks the strap with a friction grip.

A further object of the present invention is to provide a grip type buckle in which the locking action is from the underside of the strap.

Another object of the present invention is to provide a grip type buckle which is easy to attach to the shoe and easy to operate.

A further object of the present invention is to provide a grip type buckle construction which is simple in construction and easy and economical to manufacture and assemble.

With the above and other objects and advantageous features in view, my invention consists of a novel arrangement of parts more fully disclosed in the detailed description following, in conjunction with the accompanying drawings, and more particularly defined in the appended claims.

In the drawings,

FIG. 1 is a side elevation of a front portion of a shoe containing a buckle embodying the present invention.

FIG. 2 is an enlarged longitudinal section of the buckle in gripping position.

FIG. 3 is a view similar to FIG. 2 with the buckle in open position.

FIG. 4 is a front view of the buckle.

FIG. 5 is a rear view of the buckle.

FIG. 6 is an enlarged perspective view of the buckle in closed position.

Shoe buckles are normally provided with a series of openings in the strap in which the tongue of the shoe buckle can be positioned for adjustment. Buckles have been provided which frictionally grip the inserted strap both for shoes and belts. This type of buckle tends to squeeze the strap and leave marks which are undesirable especially in a shoe. The present invention is designed to provide a shoe buckle of the friction type in which the gripping action is provided from the underside of the strap face so that the strap face is not marred in any way. Furthermore, the buckle of the present invention provides what is known as a seat belt action in which it is clamped shut and opened with the flip of a lever. The buckle of the present invention is also designed to handle all thicknesses of straps without adjustment.

Referring more in detail to the drawings illustrating my invention, the buckle of the present invention comprises a rectangular base plate 10 having spaced openings 11 adjacent the rear end for riveting or otherwise attaching the buckle to a shoe. Extending integrally and upwardly from each side edge of the base 10 is a rectangular vertical wall portion 12 of shorter length than the base 10. The upper edges of the wall portions 12 are bent towards each other to form an upper plate 13 in spaced parallel relation to the base 10 and separated by a central gap opening 14.

The base 10 is provided adjacent its rear end with a slotted portion 15 the material of which has been bent upwardly to form a hook portion 16 facing the rear of the base as shown in FIGS. 2 and 3. I now provide a comparatively thin flexible rectangular plate 17 having a

large opening 18 adjacent its rear edge which is hooked around the hook 16 as illustrated. The plate 17 therefore extends from the hook 16 adjacent the front edge of the base 10 towards the rear of the base 10 and into the space between the base 10 and the plate 13.

It is contemplated that a strap 19 illustrated in dotted lines in FIG. 2 be inserted into the buckle between the plate 17 and the upper plate member 13. Gripping action is provided by the movable member which acts as a quick lever. This member comprises a pair of side plates 20 vertically positioned at each side slightly spaced from the vertical walls 12. The forward portions of the plates 20 are connected at their upper edges by a flat integral strap portion 21 having a slightly upwardly bent finger engageable tab 22. The other rear ends of the plates 20 are reduced in width and bent at right angles to form pivot members 23. The side wall portions 12, adjacent their rear edges are provided with enlarged pivot openings 24 into which the pivot members 23 extend as shown in FIG. 5. The pivot members 23 extend inwardly toward each other through the openings 24 and below the plate 17 so that the plate 17 rests upon the top edges of the portions 23 as illustrated in FIGS. 2, 3 and 5.

Now when the tab 22 is engaged by the fingers and the entire lever portion is pivoted upwardly into the position shown in FIG. 3, it will be seen that the members 23 are now turned so that their plane is parallel to the base 10. This presents only the thickness of the plate between the base 10 and the pivoted plate 17 which rests upon it. This forms an enlarged space between the plate 17 and the plate member 13. The strap 19 is now inserted into this space as shown in FIGS. 1 and 2. Now when the tab 22 and member 21 are pivoted forwardly as shown in FIG. 2, the pivot portions 23 will be swung through an arc of 90° until they are in a vertical plane as shown in FIG. 2. As they swing upwardly they push the plate 17 upwardly against the underside or reverse of the strap 19 as shown in FIG. 2. The strap 19 is therefore pinched between the plate 17 and the upper plate portions 13 which are rigid. The flexibility of the plate 17 permits the insertion of different thicknesses of straps and the flexibility of the plate 17 also reduces the amount of marring, scratching or scoring of the back of the strap.

The buckle of the present invention is thus very simple to use. That plate 10 is attached to the shoe as shown in FIG. 1, rivets being passed through the openings 11. It is immediately ready to use. The member 21 with the tab 22 is pushed upwardly into the position shown in FIG. 3 and the strap 19 can be inserted as far as it is desired. Movement of the tab 22 and member 21 downwardly into the position shown in FIG. 2 grips the strap and holds it against slipping. The pressure and movement of the operating parts are always at the rear of the strap. Also note that the pivotal movement of the members 23 causes a slight rubbing action, not against the back of the strap, but against the back of the plate 17. The plate 17 always moves gently upwardly and downwardly with relation to the strap 19. Therefore there is no scratching of the back of the strap. Also, the plate 17 presents a flat surface against the back of the strap as opposed to points or thin members. This also lengthens the life of the strap and reduces scratching or marring of the surface. The buckle is thus easy to manufacture and assemble and easy to install and operate. Other advantages of the present invention will be readily apparent to a person skilled in the art.

I claim:

1. A buckle comprising a rectangular base plate, vertical walls extending integrally vertically from each side edge of said base plate, the upper edges of said walls having integral portions extending inwardly toward each other to form an upper plate spaced from said base plate,

a gripping plate pivotally mounted on said base plate, and means for raising and lowering said gripping plate to releasably frictionally retain a strap between said upper plate and said gripping plate, said gripping plate comprising a flat flexible rectangular plate having a pivot opening adjacent its forward edge, said base plate having an integral hook portion extending upwardly adjacent its forward edge, said hook portion extending through said pivot opening, said raising and lowering means comprising a manually engageable bar extending transversely in the front of said buckle, said bar having integral side walls extending in spaced parallel relation to said vertical walls, and pivot members extending from said side walls through openings in said vertical walls, said pivot members extending under said gripping plate and having eccentric portions adapted to make contact with and raise said gripping plate on pivotal movement of said bar in one direction and to release said gripping plate on pivotal movement of said bar in the opposite direction.

2. A buckle comprising a rectangular base plate, vertical walls extending integrally vertically from each side edge of said base plate, the upper edges of said walls having integral portions extending inwardly toward each other to form an upper plate spaced from said base plate, a gripping plate pivotally mounted on said base plate, and means for raising and lowering said gripping plate to releasably frictionally retain a strap between said upper
